J. G. JONES

PHOTOGRAPHIC CARTRIDGE

Filed May 10, 1923

FIG. 11.

WITNESS
Donald S. Stewart.

INVENTOR
John G. Jones,
BY R. L. Stinchfield
N. M. Ferris
ATTORNEYS.

UNITED STATES PATENT OFFICE.

JOHN G. JONES, OF ROCHESTER, NEW YORK, ASSIGNOR TO EASTMAN KODAK COMPANY, OF ROCHESTER, NEW YORK, A CORPORATION OF NEW YORK.

PHOTOGRAPHIC CARTRIDGE.

Application filed May 10, 1923. Serial No. 638,076.

To all whom it may concern:

Be it known that I, JOHN G. JONES, a citizen of the United States of America, residing at Rochester, in the county of Monroe and State of New York, have invented certain new and useful Improvements in Photographic Cartridges, of which the following is a full, clear, and exact specification.

10 This invention relates to photographic roll film cartridges of the type commonly used in cameras and comprising a roll of film and protective paper therefor.

15 More particularly this invention has for its object the elimination of the fault commonly known as edge fog, which results from the undesired leaking or light into the margin or border of a roll film. In my Patent No. 1,454,812 granted May 8, 1923,

20 I have disclosed the use of a protective paper which, even though wider than the distance between the flanges, is adapted to buckle or be compressed upon itself, thus forming light locks at the ends of the spool. In my 25 other Patents Nos. 1,454,813 and 1,454,815 respectively, granted May 8, 1923, I have shown and claimed certain modified alternative methods of attaining this end.

30 This application relates to modifications embodying certain of the features disclosed and claimed in the above patents. More particularly it relates to protective paper in which the greater flexibility is obtained by making longitudinal grooves in the 35 paper, these grooves being of any desired cross section.

35 The advantages inherent in the forms disclosed in this application are similar to those described in the above mentioned 40 patents.

45 It is obvious that modifications embodying the invention as defined in the appended claims are possible, and I have described certain of these, referring to the figures 50 of the accompanying drawing. Those parts which are the same in the various figures bear the same reference characters in each.

Fig. 1 is a perspective view of a partially 55 unwound film cartridge, the leader strip being broken away;

Fig. 2 is a section of the protective paper;

Fig. 3 is a similar section showing the effect of lateral pressure;

Fig. 4 is a section of protective paper embodying a different form of invention;

Fig. 5 is a similar section showing the effect of lateral pressure;

Fig. 6 is a section of protective paper embodying still another form of my invention;

Fig. 7 is a similar section showing the effect of lateral pressure;

Fig. 8 is a section of protective paper embodying yet another form of my invention;

Fig. 9 is a similar section showing the effect of lateral pressure;

Fig. 10 is a perspective view of a motion picture reel having wound thereon motion picture film with lead strips at the end embodying my invention, the whole being cut to show the section;

Fig. 11 is a section of the paper used thereon, with a fragment of paper shown in perspective.

It is to be understood that in all of the figures the thickness of the protective paper is exaggerated in order to show more clearly the nature of the invention. It is further to be understood that the figures are not drawn to scale.

Upon a film spool of ordinary character comprising a core A and metallic end flanges C, are interwound a strip of film F and backing paper 1, to which the film is attached by usual sticker band S. The spool has the customary axial pintle opening (not shown) at one end and winding slot E at the other. As thus far described, the cartridge is in every way similar to that in general use. The protective backing paper 1, however, is cut wider than the distance between the interior surfaces of the flange C, and there are formed in it a series of longitudinal parallel grooves 2. As is common, the backing paper 1 extends the full length of the film and beyond it at each end to form safety leader strips. In this form the longitudinal grooves extend the full length of this backing strip. When the paper and film are thus interwound on the spool and the paper is thus subjected to lateral pressure, the thinner portions at the bottoms of the grooves 2, which are of greater flexibility, will tend to buckle. This action will be understood by reference to

Figs. 2 and 3. In the form here illustrated the grooves have flat bottoms, leaving thin portions of uniform thickness 3, and these tend to buckle, as indicated at 4. It will

be noted that the band as a whole is laterally compressed without being piled up or made of greater thickness so that a coil of such material will not be distorted in an objectionable way.

As shown in these figures grooves are formed at regular intervals across the width of the paper, but I may form them with non-uniform spaces between them, as shown in Fig. 4, where the backing paper 11 has two grooves 12 rather close together near each margin, and a wide central or medium space 15 between the two sets of grooves. These grooves have flat bottoms leaving thin portions 13 of uniform thickness. When submitted to lateral pressure they tend to crinkle, as indicated at 14.

The grooves may have any desired cross section, round bottomed grooves 22 being shown in the paper 21 in Fig. 6. The effects of compression are indicated in Fig. 7 at 24.

If desired, grooves may be made on opposite surfaces of the paper, and when this is done I have found it advantageous to make them slightly out of registry, two rounded grooves 32 being shown so situated on the paper 31 in Fig. 8. They have a tendency to crinkle under lateral compression, as indicated at 34 in Fig. 9.

In Fig. 10 is shown a coil of motion picture film 40 having at each end thereof a lead strip 41, in the median line of each of which is a longitudinal rounded groove 42. This is better shown in an enlarged section in Fig. 11. These are shown wound on the usual type of reel 45 used in motion picture cameras and having a core 43 and flanges 44. In practice the number of convolutions would be greater than here shown and no attempt is made in this figure to show the crinkling of the paper due to compression. It is to be understood, however, that the width of the film is slightly less than the distance between the flanges 44, while the width of the paper is slightly greater.

This embodiment of my invention has been found useful for reels designed to be used by amateurs where the highest degree of care is not to be expected and where a convenient daylight loading reel or magazine is particularly desirable.

I have found that with paper having a width of about five-eighths of an inch and intended for use in a small portable motion picture camera the groove or thinned portion may have a width of about an eighth of an inch and may have a depth of a half or two-thirds of the thickness of the paper, the latter being .0035 or .004 inch thick and of good quality material. The dimensions of the grooves will, of course, depend very largely on the dimensions and quality of the material and will have to be determined for the particular circumstances.

The above dimensions are therefore merely illustrative and are given as an instance that has been found satisfactory. In general, the groove is wide in proportion to its depth.

In practice the crinkling is not nearly as apparent as might seem to be indicated in the drawing and it has been shown there in an exaggerated manner in order more clearly to illustrate the theory of operation.

Even though the paper is not originally cut wider than the distance between the flanges, it is useful to have it compressible in the manner indicated, since it is liable to swell under changing atmospheric conditions, and also because if the paper tends to run slightly awry in the camera and creep toward one side the compressibility will permit it still to be drawn through the camera without excessive binding.

In motion picture film and lead strips it is customary to have a row of perforations along each margin, as shown at 46 in Fig. 11. It is therefore undesirable to weaken the paper along these margins where it is subjected to pulling strain and hence it is especially desirable to place the groove in the median portion between the rows of perforations.

When in the claims the term groove is used, it is intended to indicate a depression with two side walls, there being portions of normal thickness on each side of the thinnest portion caused by such depression.

It is obvious that numerous embodiments of my invention are possible; and it is to be understood that the disclosure herein is illustrative, and that I contemplate as within the scope of my invention all such equivalents and modifications as fall within the scope of the appended claims.

Having thus described my invention, what I claim as new and desire to secure by Letters Patent is:

1. An article of manufacture comprising a roll of sensitized material, a support therefor comprising spaced end flanges, and a strip of protective material coiled around said sensitized material and having a longitudinal groove formed therein.

2. An article of manufacture comprising a roll of sensitized material, a support therefor comprising spaced end flanges, and a strip of protective material coiled around said sensitized material and having a longitudinal groove formed therein, the width of the strip being greater than the distance between the flanges.

3. A photographic film cartridge comprising a spool with spaced end flanges having flat inner facing surfaces, strip material, comprising photographically sensitive material and protective material, wound on said spool and including lead strips of protective material, said lead

- strips each having a longitudinal groove therein.
4. A photographic film cartridge comprising a spool with spaced end flanges having flat inner facing surfaces, strip material, comprising photographically sensitive material and protective material, wound on said spool and including lead strips of protective material, said lead strips each having a longitudinal groove therein, and being wider than the distance between the flanges.
5. An article of manufacture comprising a reel with a core and spaced flanges, a strip of sensitive material wound thereon and having attached thereto at each end a lead strip, said lead strips each having a longitudinal groove therein.
6. An article of manufacture comprising a reel with a core and spaced flanges, a strip of sensitive material wound thereon and having attached thereto at each end a lead strip, said lead strips each having a longitudinal groove therein, and the lead strips only being wider than the distance between the flanges.
7. An article of manufacture comprising a reel with a core and spaced flanges, strip material comprising photographically sensitive material wound on said spool and including lead strips of protective material, said lead strips each having a longitudinal groove in its median portions.
8. An article of manufacture comprising a reel with a core and spaced flanges, a strip of motion picture film wound thereon and having attached thereto at each end a lead strip, said lead strips having a row of perforations in each margin and each lead
- strip having a longitudinal groove in the median portion between the rows of perforations.
9. An article of manufacture comprising a roll of sensitized material, a strip of protective material coiled around said sensitized material and having a longitudinal groove formed therein.
10. An article of manufacture comprising a reel with a core and spaced flanges, a strip of sensitive material wound thereon and having attached thereto at each end a lead strip, said lead strips each having a single central longitudinal groove therein.
11. An article of manufacture comprising a reel with a core and spaced flanges, a strip of motion picture film wound thereon and having attached thereto at each end a lead strip, said lead strips each having a row of perforations in each margin and a single, central longitudinal groove therein.
12. An article of manufacture comprising a roll of sensitized material, a strip of protective material coiled around said sensitized material and having a longitudinal groove therein, the depth of the groove being greatest at the center and decreasing toward the edges thereof.
13. An article of manufacture comprising a roll of sensitized material, a strip of protective material coiled around said sensitized material and having a longitudinal groove therein, the width of the groove being greater than a sixth of the width of the strip.

Signed at Rochester, N. Y., this 3rd day of 75
May 1923.

JOHN G. JONES.
